UNITED STATES PATENT OFFICE

KENNETH J. TOBIN, OF CHICAGO, ILLINOIS, ASSIGNOR TO CAMEL COMPANY, OF CHICAGO, ILLINOIS, A CORPORATION OF ILLINOIS

CAR CONSTRUCTION

Application filed December 11, 1929. Serial No. 413,320.

The invention relates to car construction and more particularly to the construction of car ends. The invention has for an object the construction of a car end whereby said construction presents substantially qualities of uniform strength.

It is a further object of this invention to provide bracket means for car ends, said bracket means being adapted to intimately tie the end framing structure to the underframe of railway house cars.

It is also an object of this invention to utilize bracket means, which bracket means provides a connection between the car underframe and end frame, and which affords means for hinging end doors to the end frame.

Other objects and advantages of the present invention will become more apparent as the description thereof proceeds, taken in connection with the drawings forming a part thereof, and in which:

Figure 1 is an elevational view of a car end construction.

Figure 2 is a view of Figure 3 from the left thereof.

Figure 3 is an enlarged detail view of the lower left hand corner of Figure 1.

Figure 4 is an elevation of a combined bracket and hinge butt.

Figures 5 and 6 are sectional views taken on lines 5—5 and 6—6, respectively, of Figure 3.

In the drawings the numeral 10 designates, as a whole, a railway house car which has applied thereto a roof 11 of any desired construction. An end plate 12 is provided, the ends 13 of which are curved downwardly. Corner posts 14—14 are shown extending from said downwardly curved portions of the end plate to and overlapping the side sill 16 to which it is secured, as hereinafter set forth. It is noted that the end plate 12, in conjunction with the corner posts 14—14 and an end sill 15, constitute in effect a frame-work for the car end. In order to close this framework and provide a substantially solid end construction, a pair of doors 17—18 are shown. These doors comprise panels 19 and 20, said panels being preferably corrugated as shown. A door frame 21, formed of an

inverted U shaped member preferably Z-shaped in section, is provided. The door frame is attached to the corner posts 14—14 and is also secured to the end plate 12. It is noted that the door frame has a curved portion extending between the horizontal and vertical parts thereof, which curved portion follows the contour of the curved ends of the end plate 12. Hinges 22 are employed for mounting the door ends on the end frame. In order to lock the doors which overlap at their adjacent margins with the doors in such closed position, a swinging locking bar 23, coacting with upper and lower keepers 25 and 26 mounted above and below the doors, is utilized. This locking bar is pivotally mounted as shown at 24 on the overlapping door. Stops 27 and 28 are employed for limiting the opening and closing movements of the locking bar. When closed, an abutment member 29 is utilized to prevent accidental pivotal displacement of said bar. Additional locking bars of any desired construction, such as shown at 30—30, may be utilized.

The end plate 12, corner post 14, and the inverted U-shaped door frame member, together with the gradually curved parts of the end plate and door frame, constitute a substantially rigid and strong construction for the upper portion of the car end. Heretofore, however, the construction at the lower ends of the corner posts, where said posts are attached to the underframe of the car, has provided a comparatively weak condition, which condition the present improvements are designed to overcome. There is employed, consequently, a plurality of brackets 31—31, shown in the present embodiment as formed of castings, although formed brackets may, if desired, be used, one of such brackets being employed at each lower corner of the end construction. These brackets are riveted or otherwise rigidly attached as shown at 32 and 33 to the end sill 15 and the threshold member 34, a portion of which overlies the vertical leg of the end sill, said end sill being illustrated in figure 2 as an angle member. The brackets are offset at 35 (Figures 3 and 4) in order to receive the overlapping part of the threshold plate. The brackets are also rig-

idly secured to the corner posts 14 and end frame member 21 by means of rivets 36 and 37. The brackets are also formed with a vertical portion 38 offset as shown in Figure 5 of the drawings, between which offset and its adjacent corner post a portion of the door frame member is adapted to be received. The brackets 31 are also preferably formed with abutment members 39.

10 By employment of these brackets it is apparent that the frame members 14, 15 and 21 are all rigidly tied together so as to present a strong construction at the lower portion of the end frame. As a further means to secure 15 this construction, additional brackets 40 may be secured to the end sill, side sill and corner posts. As shown in Figure 6 of the drawings, the bracket 40 is secured to the end sill 15 by means of rivets 32, which pass through the 20 bracket member 31 to secure said bracket in position. Rivets 41 connect the brackets 40 to the side sill 16 and corner posts 14. The connection between the inner bracket member 40, the side sill 16 and the end sill 15, is also effected by means of rivets 42, said rivets passing through the flange 43 of the channel shaped side sill 16.

To utilize the developed strength at the lower corners of the end frame construction 30 and to relieve the corner posts of part of the strain produced in them by the end doors hinged thereto, the brackets 31 are provided, preferably integral therewith, with hinge butts 44. These hinge butts carry knuckles 35 45 which are spaced vertically relative to each other. Aligned openings 46 are provided in said knuckles. Corresponding knuckles are formed on the hinge straps 47 secured to the doors 17 and 18. The knuckles 40 on the hinge straps have aligned vertical openings which are adapted when the door is hung, to align with the openings 46 formed in the knuckles on the hinge butt 44. The hinge pin 48 is adapted to pass through said 45 aligned openings whereby a hinge similar to the hinge 22 is provided. Extending through the knuckles 45 are openings 49 through which the rivets 37 are adapted to extend in order to secure the hinge butt to the 50 door frame and corner posts. Ribs 50 are shown utilized for the purpose of strengthening the hinge butts 44.

It is believed to be apparent from the foregoing construction that the strain on the 55 hinge butt will be carried in large measure by means of the brackets 31 directly to the rigid end and side sill members with a consequent reduction in the strain on the corner posts. Moreover, the construction of the 60 hinge butt and bracket provides for automatic proper disposal of the door in its frame. It also appears, from the foregoing description, that weaving at the lower corners of the car end construction is substantially obviated.

I claim:

1. In a house car, in combination, a corner post, a vertical door framing member secured thereto, an end sill and combined bracket and hinge butt means connecting said post and framing member to said end sill. 70

2. End construction for house cars, in combination, an end plate, corner posts, a door framing member secured to said end plate and corner posts, an end sill and combined bracket and hinge butt means connecting the lower ends of said corner posts and framing member to said end sill. 75

3. End construction for house cars, in combination, an end plate, an end sill, corner posts secured to said end plate and end sill, a framing member contiguous with said end plate and corner posts and secured thereto, and combined bracket and hinge butt members securing the end sill to the framing member and corner posts, said members being offset and said framing member having a portion thereof positioned between said offset and said corner posts. 80 85

4. In an end frame for house cars, in combination, corner posts, an end sill, brackets comprising substantially angularly shaped castings secured to said corner posts and end sill, a portion of said brackets constituting hinge butts, panels positioned in said frame and hinge straps carried by said panels and adapted to be connected with said hinge butts in hinged relationship. 90 95

5. End construction for house cars, in combination, an end plate, an end sill, a side sill, corner posts secured to said end plate, outer brackets secured to said corner posts and said end sill, inner brackets, said side sill being positioned between said corner posts and said inner brackets, said end sill being positioned between said inner and outer brackets and means connecting said parts together. 100 105

6. Car construction, in combination, a frame, said frame comprising horizontal and vertical members, a bracket connecting said members and secured thereto, said bracket being provided with a hinge butt. 110

7. Car construction, in combination, a frame, said frame comprising horizontal and vertical members, a bracket connecting said members and secured thereto, said bracket being provided with a hinge butt, said butt being integral with said bracket. 115

8. Car construction, in combination, a frame, said frame comprising horizontal and vertical members, a bracket connecting said members and secured thereto, said bracket being provided with a hinge butt, said bracket and hinge butt comprising an integral casting. 120 125

9. Bracket means comprising a connecting portion, said portion being provided with an extension substantially at right angles to said connecting portion, said extension carrying spaced hinge knuckles and aligned openings 130

in said knuckles, adjacent portions of said connecting portion and extension being offset and said knuckles being carried by the offset portion on said extension.

10. Bracket means comprising a casting, 5 said casting having a member integral therewith and extending beyond a marginal portion thereof, spaced bosses integral with said member and projecting outwardly therefrom, and aligned openings extending through said 10 bosses whereby said member and bosses comprise a hinge butt integral with said casting.

Signed at Chicago, Illinois, this 5th day of December, 1929.

KENNETH J. TOBIN.
